DARNING DEVICE

William Hofgesang, Avenel, N. J., assignor to
The Singer Manufacturing Company, Elizabeth, N. J., a corporation of New Jersey

Application November 15, 1941, Serial No. 419,254

3 Claims. (Cl. 112—121)

This invention relates to thread holders for use in darning and has for one of its objectives the provision of an improved holder which will effectively hold the threads or strands of yarn under tension and in their correct position.

Another object of the invention is to form the holder from a single piece of wire, and to provide a construction in which the threads or yarn strands are gripped with a uniform pressure.

A still further object of the invention is to provide a holder which is readily threaded, can be manufactured at low cost, and which is simple and easy to use in performing darning operations on various kinds of material.

With the above and other objects in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

In the drawing, Fig. 1 is a perspective view showing my improved thread or yarn holder as it is used with the ordinary household sewing machine.

Fig. 2 is a perspective view of the holder.

Fig. 3 is a bottom plan view of my improved holder, and Fig. 4 is a section taken along the line 4—4 of Fig. 3.

As shown in the embodiment selected for illustration, my improved holder is made from a single piece of wire, preferably, spring wire, and beginning with the arm 10, the wire is bent at a right angle at the point 11 to form a yoke portion 12. The wire is then bent at 13 and 14 to form the U-shaped arm 15 which is arranged parallel to the arm 10. The wire is then bent at 16, 17, 18 and 19 to form the upwardly inclined handle portions 20, 21 and 22. The wire is bent at 23 to form the U-shaped arm 24, and at 25 to form the yoke portion 26. Finally, the wire is bent at right angles at 27 and terminates at the end of the arm 28. A rectangular piece of sheet metal 30 has three of its marginal edges clamped about the handle portions 20, 21 and 22, and its fourth marginal edge encircles and clamps together the yoke portions 12 and 26.

The two limbs of the U-shaped arms 15 and 24 are spaced apart a distance slightly greater than the diameter of the wire used, forming, in effect, a slot, and the arms 10 and 28 are located within the space between the limbs. Both the

U-shaped arms 15 and 24 and the limbs 10 and 28 lie in the same plane (see Fig. 4).

It will be observed that the thread-holder is forked and the free end of each of the U-shaped arms 15 and 24 is bent upwardly and the free ends of the arms 10 and 28 extend beyond the ends of the arms 15 and 24. This construction forms flared mouths which facilitate the introduction of the threads.

My improved darning device is used in the following manner:

Preferably, threads indicated generally as T in the drawing, are pulled from the body material which is to be repaired and are then introduced between the U-shaped arms 15 and 24 and the arms 10 and 28 so that they lie in spaced parallel relation with the distance between the threads about equal to the distance between the woof threads of the body material. It will be understood that it is not necessary to use threads drawn from the body material to be repaired, but that any threads may be used. However, the color of the material is more perfectly matched and any fading or other variation in color is automatically taken care of when the threads are drawn from the material. After the darning device or holder has been prepared by placing therein as many threads as are necessary to cover the hole to be repaired, the body material is placed in a darning ring 31, as shown in Fig. 1, the darning ring is then placed on the work-plate 32 of an ordinary household sewing machine and the darning device or thread holder with the threads therein is placed over the hole to be darned. The machine is then operated, the presser-foot having been removed, and the darning ring and holder are moved by hand back and forth so that the threads in the holder are stitched to the marginal edge of the hole by lines of stitching which run at right angles to the length of the thread in the holder and parallel to the warp threads of the fabric. It is preferable to form the first line of stitches closely adjacent and parallel to either the arms 15 or 24. It will be understood that the thread used for the needle and bobbin correspond in color and texture to the thread in the holder, and that as the threads in the holder correspond to the woof threads of the material and the thread of the needle corresponds to the warp thread of the material, the material itself is closely simulated.

After the above described operation has been completed, the darning device is grasped by the upstanding portion and pulled towards the oper-

ator to release the ends of the thread, which may then be either cut off with a pair of scissors or sewed down.

By having the U-shaped arms 15 and 24 spaced apart a greater distance than the diameter of the wire used in making the device, the thread when it is placed in the holder is urged upwardly by the two resilient arms 10 and 28 so that it is slightly bowed between the limbs of the U-shaped arms. This arrangement and construction permits a wide variation in the thickness of the threads which may be used with this device.

From the foregoing description considered in connection with the accompanying drawing, the construction, manner of operation and several advantages of my improved darning device will be clearly and fully understood. It is apparent that such a device has a wide variety of uses and it will be understood that the form, construction and arrangement of elements employed are susceptible of material variation. Therefore, the privilege is reserved of resorting to all such legitimate changes therein as may be fairly embodied within the spirit of the accompanying claims.

Having thus set forth the nature of the invention, what I claim herein is:

1. A thread holder for use in darning on a sewing machine having a flat work supporting surface comprising, a forked member having an upstanding handle, a pair of coplanar and parallel arms disposed entirely at one side of the handle so that they will rest flat upon the work, each arm being U-shaped, and a second pair of arms

disposed between the limbs of the U-shaped arms, said second pair of arms being resilient and all of said arms lying substantially in the same plane and extending forwardly from said handle.

5 2. A thread holder for use in darning on a sewing machine having a flat work supporting surface comprising, a forked member having an upstanding handle, a pair of coplanar and parallel arms disposed entirely at one side of the handle so that they will rest flat upon the work, each of said arms extending forwardly from the handle and being U-shaped, a second pair of arms extending forwardly from the handle, said second pair of arms being resilient and cooperating with the first mentioned arms to hold yarn threads therebetween, one of said pairs of arms being longer than the other and the free end of the shorter pair of arms being bent away from the longer pair of arms to form a throat to facilitate the placing of yarn between said pairs of arms.

15 3. A thread holder for use in darning on a sewing machine having a flat work supporting surface comprising, a forked member having an upstanding handle, a pair of coplanar and parallel arms disposed entirely at one side of the handle so that they will rest flat upon the work, each of said arms being U-shaped, a second pair of parallel arms superposed upon the first pair of arms, all of said arms being in substantially the same plane and formed from a single piece of spring wire, the free ends of said arms being remote from said handle.

20 WILLIAM HOFGESANG.
